UNITED STATES PATENT OFFICE.

JAMES F. STRUBLE, OF HUTCHINSON, KANSAS.

WINDMILL GEARING.

Application filed March 1, 1922. Serial No. 540,103.

To all whom it may concern:

Be it known that I, JAMES F. STRUBLE, a citizen of the United States, and resident of Hutchinson, in the county of Reno and State 5 of Kansas, have invented certain new and useful Improvements in Windmill Gearing, of which the following is a specification.

This invention relates to power transmitting devices and more particularly to a means 10 for converting a rotary into a reciprocatory motion.

An important object of this invention is to provide a windmill gearing having novel means whereby the pump rod is caused to reciprocate with a uniform and steady movement thereby eliminating the possibility of serious breakage of the parts and excessive wear.

A further object of this invention resides 20 in the novel form of housing within which the power transmitting members operate.

Specifically this invention is an improvement over my co-pending application Serial Number 510,748 in that it provides simple 25 and reliable means whereby the pump rod is maintained in approximate alinement with the main power transmitting gear so that the strain on the parts is reduced to a minimum and so that lost motion is also reduced to a 30 minimum. By reason of the improvement described the housing or casing may be moved laterally in a highly expeditious manner when the housing completes its stroke in one direction.

35 A further object is to provide a power transmitting member for windmills which is simple to operate, of highly simplified construction and cheap to manufacture.

Other objects and advantages of the invention 40 will be apparent during the course of the following description.

In the accompanying drawing:

Figure 1 is a front elevation of the improved power transmitting member.

45 Figure 2 is a vertical sectional view through the same.

Figure 3 is a horizontal sectional view taken on line 3—3 of Figure 1.

Figure 4 is a front elevation of a modified 50 form of the invention.

Figure 5 is a horizontal sectional view taken on line 5—5 of Figure 4.

Figure 6 is a detail view of a bracket em-

bodied in the invention, which bracket is used in connection with a spring embodied in the 55 invention.

In the drawing the numeral 5 generally designates a housing which is cast in one piece and is of elongated formation. The housing has its sides formed with a continuous outwardly extending projection constituting a reinforcing member 6 and a continuous channel 7 through which a power transmitting gear 8 travels. With reference to Figures 2 and 3 it will be seen that the 60 outer portions of the gear travel in the gear channel 7 and that the hub 9 of the gear 8 rotatably contacts with the flanges 10 and 11 on opposite sides of the channel 7.

A rack 12 of elongated formation is secured within the housing by means of bolts 13 which pass through the back 14 of the housing. The rear side of the elongated rack 12 is provided with bosses 15 which cooperate with the flanges 16 formed at the 65 edge of the rack in spacing the body of the rack from contact with the back 14. The base 17 of the elongated rack 12 is extended beyond the teeth 18 of the rack so as to form a gear contact and guiding surface.

A cover plate 20 is firmly secured to the elongated rack 12 and extends beyond the same to cooperate with the extended portion of the base in providing a second channel 7 arranged in close relation to the channel 7 75 and slidably receives a portion of the power transmitting gear 8 so that the gear will be correctly guided. The end portions of the cover plate 20 are extended outwardly to provide a flange 21 which is arranged inwardly of the flange 10 and contacts with the hub 9 of the gear. Specifically the flanges 10 and 21 provide a continuous slot 85 of oval-shaped formation to slidably receive and guide one of the hubs 9 of the gear.

The gear 8 is rotated about the stationary axis passing through the drive shaft 24 of the usual wind wheel. It is thus seen that the operation of the gear 8 will cause the housing to move vertically and laterally and thereby reciprocate the pump rod 26.

The pump rod 26 has its upper end formed with a pair of spaced arms 27 to which a pulley 28 is connected, the said pulley being slidable in a slot 30 in a depending portion 31 of the housing. The pump rod 26 is 100 105

at all times arranged directly beneath the gear 8 so that the strain on the several parts is uniformly distributed.

In operation the housing is suspended by a coiled spring 35 connected at its upper end to a bracekt 36. The coiled spring 35 serves as a steadyng means for the housing and also holds the housing in position in the event of breakage of the gear 8 on the drive shaft. In this manner the housing would be prevented from falling onto some other part of the wind wheel tower and possibly breaking the same.

The several parts of the power transmitting device may be readily and conveniently reversed when partly worn so that the wear will be uniformly distributed.

As illustrated in Figure 1 the depending portion 31 is provided with a bracket 90 held in position by a cap screw 91, the said bracket being formed with a disc shaped head 92 with which one end of a coil spring 93 is engaged. The other end of the coil spring 93 bears against the end of the pump rod 26 and thereby serves as an efficient and positive means for alining the pump rod with the gear 8 so that the lateral movement of the housing is facilitated, when it reaches the end of this stroke. It is obvious, of course, that the gear 8 does not move vertically, but that the housing 5 is the movable member and travels in an oval path. However, the movement of the pump rod 26 is substantially vertical because of the presence of the coil spring 93.

In carrying out the invention the coil spring 93 may be located within the depending portion 31 so as to save space.

In the form of the invention illustrated in Figures 4 and 5 the rack 40 is cast integral with the housing 41 and the gear 42 operates in opposed channels in the housing. The cover plate 43 may be held in spaced relation by bolts 44 arranged in spaced parallel relation and extended through the back of the housing and the rack 40.

Having thus described the invention what is claimed is:

1. A windmill gearing comprising a housing having a continuous channel, a rack arranged in said housing and forming one side of said channel, a gear movable in said channel and engaged with said rack, a rod slidably connected to said housing, and a spring carried by said housing and urging the rod laterally with respect to the housing.

2. A windmill gearing comprising a housing having a continuous channel, a rack arranged in said housing and forming one side of said channel, a gear movable in said channel and engaged with said rack, a cover plate extending over said gear to guide the gear and hold the same in position, a rod slidably connected to said housing,

and a spring carried by said housing and engaging said rod for urging the housing laterally with respect to the rod.

3. A windmill gearing comprising a housing having a continuous channel, a rack arranged in said housing and forming one side of said channel, a gear movable in said channel and engaged with said rack, and a cover plate extending over said gear to guide the gear and hold the same in position, said housing and said cover plate being provided with outwardly directed guiding devices.

4. A windmill gearing comprising a housing provided with a reinforcing projection defining a gear channel, a rack arranged within said housing and having an extended portion engaged with said housing, and a cover plate secured to said rack and extending beyond the same to cooperate with the extended portion of the rack in defining a second gear channel arranged in opposed relation to said first named gear channel.

5. A windmill gearing comprising a housing provided with an outwardly extending reinforcing projection defining a gear channel, a rack arranged within said housing and having an extended portion engaged with said housing, a cover plate secured to said rack and extending beyond the same to cooperate with the extended portion of the rack in defining a second gear channel arranged in opposed relation to said first named gear channel, and a gear movable in said channel and having hubs contacting with said housing and rack and being guided thereby.

6. A windmill gearing comprising a housing having an outwardly extending reinforcing projection defining a gear channel, a rack arranged within said housing and having an extended portion engaged with said housing, a cover plate secured to said rack and extending beyond the same to cooperate with the extended portion of the rack in defining a second gear channel arranged in opposed relation to said first named gear channel, a gear movable in said channel and having hubs contacting with said housing and rack and being guided thereby, and means yieldably supporting said housing.

7. A windmill gearing comprising a housing having outwardly projecting reinforcing portions constituting a gear channel and a pair of flanges on opposite sides of said channel, a rack arranged within said housing and having an extended portion provided with a laterally projecting flange contacting with said housing and arranged in spaced relation to one of said first named flanges, a cover plate secured to said rack and extending beyond the same to define a second channel arranged in opposed relation to said first named channel, the edge por-

tion of said cover plate being provided with an outwardly directed flange arranged in spaced relation to one of said first named flanges, and a gear movable in said first and second named channels and having hubs lying between said flanges, said housing being provided with means whereby a pump rod may be connected thereto.

8. A windmill gearing comprising a housing having outwardly projecting reinforcing portions constituting a gear channel and a pair of flanges on opposite sides of said channel, a rack arranged within said housing and having an extended portion provided with a laterally projecting flange arranged in spaced relation to one of said first named flanges, a cover plate secured to said rack and extending beyond the same to define a second channel arranged in opposed relation to said first named channel, the edge portion of said cover plate being provided with an outwardly directed flange arranged in spaced relation to one of said first named flanges, a gear movable in said first and second named channels and having hubs lying between said flanges, said housing being pro-

vided with means whereby a pump rod may be connected thereto, and means yieldably supporting said housing.

9. A power transmitting device for windmills comprising a housing, a rack therein, a gear associated with said rack, said housing being provided with a depending portion having a slot, and a pump rod having a pair of spaced arms provided with a pulley 30 35 slidable in said slot.

10. A windmill gearing comprising a housing, a rack arranged therein, a power gear engaged with said rack whereby to move the housing vertically, a rod slidably connected to said housing, and a spring having connection with said housing and rod and urging one laterally with respect to the other.

11. The combination of a housing, a rack 45 secured thereto, a power gear engaged with said rack, a rod slidably connected to said housing, a bracket secured to said housing and having a head, and a coil spring confined between said head and said rod.

JAMES F. STRUBLE.
